UNITED STATES PATENT OFFICE.

ITHAMER N. F. RANDOLPH, OF IOLA, KANSAS.

OIL-BURNER.

1,072,773.

Specification of Letters Patent.

Patented Sept. 9, 1913.

Application filed April 1, 1912. Serial No. 687,737.

To all whom it may concern:

Be it known that I, ITHAMER N. F. RANDOLPH, a citizen of the United States, residing at Iola, in the county of Allen and State of Kansas, have invented a new and useful Oil-Burner, of which the following is a specification:

This invention relates to oil burners.

The primary object of this invention is to construct a device of this character which will produce steam which commingles with the oil.

A further object is to so construct the apparatus that various changes may be made in the oil and steam supply, that light or heavy oil may be readily burned.

A still further object is to provide means for supplying air to the mixture and regulating said supply.

Another object is to provide means for removing objectionable material from the oil.

A still further object is to construct a burner that may be readily placed in stoves now in use without materially altering their construction, and which may, with certain changes, be adapted for furnaces and engines.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings, forming a part of this specification,—Figure 1 is a side elevation, the stove in which the apparatus is placed being shown in section. Fig. 2 a section on the line 2—2 of Fig. 1. Fig. 3 a section taken transversely through the generator and drip pan. Fig. 4 a detail view of one of the dials with which the valve members are equipped. Fig. 5 a perspective view of the nozzle which is used in the burning of heavy oil. Fig. 6 an elevation partly in section, of the apparatus equipped for burning light oil. Fig. 7 a detail view of the damper utilized in the starting of the fire. Fig. 8 a top plan view of the form shown in Fig. 1. Fig. 9 an elevation of a slightly modified form of burner. Fig. 10 is a perspective view of one of the locking members used to hold the adapting plates in position. Fig. 11 a detail view showing the form of burner utilized in the burning of heavy oil. Fig. 12 is a view in elevation of the supporting plate and the movable adapting plate secured thereto.

Fig. 11 a detail view showing the form of burner utilized in the burning of heavy oil. Fig. 12 is a view in elevation of the supporting plate and the movable adapting plate secured thereto.

In the drawings: 10 designates the compartment in the stove in which the apparatus is inserted, the stove being provided with the usual grate 11. In the form shown in Fig. 1 the apparatus consists of a pan 12 which forms a support for the same, said pan resting upon the grate 11. The plate 14 is secured to the pan adjacent one of its ends, the pan being formed with upstanding lugs 15, bolts passing through said lugs and said plate. This construction is designed for the burning of light oil, the construction shown in Fig. 9 being designed for use in the burning of heavy oil, being more adapted for furnaces. In the form shown in Figs. 1, 6 and 8 the integral flange 14 of the frusto-conical hood 17 is attached to the lugs 15, this hood being provided with an interiorly formed lug or support 19. This support is provided with passages 20 and 21, the passage 20 which is disposed longitudinally of the support communicating with the chamber 22 of the hood. The oil supply pipe 27 is screwed into the hood, said pipe communicating with the passage 21. The tank for the supply of oil may be located at a point remote from the burner, that is, the same may be arranged on the exterior of the house in which the burner is used. Disposed at a point adjacent said tank and between said tank and the burner is a cylinder 28 which removes any objectionable material from the oil, the cylinder containing any suitable means for performing the above function, the precise construction of which is not concerned in the present invention. The supply of oil in the pipe is regulated by the valve 30. This valve, as well as the valve hereinafter mentioned is provided with the dial shown in Fig. 4 in order that the supply may be accurately regulated. The steam generator 32 is supported adjacent one edge of the pan, being spaced from the same as shown in Fig. 3. The generator is connected to the pipe 33 which passes through the plate 14 and supplies water to the generator, the flow of water being controlled by the valve 34. The water enters the generator and when steam is generated the same passes

through the steam pipe 35 to the pipe 38 in the support 19 and which communicates with the passage 20. This pipe is connected to the drain 39, a valve 40 being arranged in said connection, this valve being manipulated to allow a certain portion of the steam generated in the steam generator to escape and to thereby indirectly regulate the supply of steam passing through the passage 20, commingling with the oil, the mixture passing out of the passage into the flared terminal of said passage, being sprayed upon the pan.

The opening 40 at the rear of the conical hood is closed by the damper shown in detail in Fig. 7, this damper being utilized when the fire is being started. The damper consists of a plate 41 which is rotatably supported by the hood, the slot 42 being adjusted with respect to the opening 40 to regulate the supply of air. The plate is formed with the arcuate slot 43, an adjusting screw 44 locking the plate in any desired position, the opening thus being held in proper relation without danger of the damper being accidentally rotated.

In operation water is supplied to the generator 32, fire being started in the pan, the damper plate being rotated to open the end of the hood, and steam generated. When steam is generated the oil inlet valve is opened and oil supplied to the pipe 27, this oil rising through the passage 21 to the passage 20. The steam is admitted to the passage 20, the oil thus being sprayed on the pan 12, the oil and steam being commingled with air, thereby forming a perfect mixture for the burner. Attention is called to the fact that a perfect mixture of oil and steam is secured, the combined oil and steam being forced under pressure creating a suction which commingles air with the mixture thus securing a perfect fuel.

It will be noted that various changes may be made in the arrangement of the steam and oil pipes without departing from the spirit of the invention and that the same may be readily placed in furnaces and stoves, the fire boxes of which vary in size.

As illustrated in Fig. 11 the frusto-conical hood member is formed integral with the outstanding plate 14 which plate 14 is rigidly secured to the pan 12 and supported thereby. In order to lock the entire device against shifting and to further provide means whereby the oil burner may be attached to stoves of varying sizes, the slideable plates 18 are secured to the plate 14 and are adapted to be rigidly secured thereto. The slideable plates 18 are provided with longitudinal slots 48, suitable locking means co-operating therewith to hold the said plates in position. The locking members 51 as illustrated in detail in Fig. 10 are adapted to engage a portion of the stove, the same

being more clearly illustrated in Fig. 1 of the drawings. The locking members 51 are also adapted to hold the slideable plates 18 rigid with respect to the plates 14. From the foregoing it will be apparent that the pan 12 serves as a supporting means and the plates 18 and pivoted locking members 51 prevent the entire device from shifting with relation to the stove or furnace to which my improved device has been secured.

The form shown in Figs. 9 and 11 is designed for use with heavy oil, mention being made of the fact that the steam pressure is slightly less than the pressure at which the oil is supplied. In this form the hood is provided with passages 20' and 21' which communicate, and a passage 25 being disposed longitudinally of the support communicating with the chamber 22 of the hood. The nozzle 52 is screwed into the support the bore 53 of the nozzle communicating with the passage 20' the nozzle being formed with a flared delivering end 54 which projects beyond the hood. In this form the steam generator will have a water supply pipe 55 which is controlled by the valve 56, the steam generated passing through the return pipe 57 and to the coupling 59. The valve 60 connecting said coupling with the exhaust or drain pipe 39, a pipe 61 connects this coupling with the steam passage 21' and has a check valve 65 located therein said check valve discharging toward the steam passage 21'. The oil supply pipe 62 communicates with the passage 20' said supply of oil being regulated by the valve 63 which is disposed between the tank which receives the residue and the burner. It will be noted that the conducting passages of the oil and steam are formed reversed with respect to those shown in the form for burning the lighter oil, the construction being practically the same with the exception of the addition of the nozzle 52.

It will be noted that various other changes may be made in the arrangement of the oil and steam supply pipe for the burning of various grades of oil, the structure shown for the burning of heavy oil in which the nozzle is employed being particularly adapted for use in connection with furnaces or engines.

The many advantages of a construction of this character will be clearly apparent and it will be noted that the same may be easily and economically manufactured and that the device may be readily positioned within stove openings which vary in size. It will also be noted that the structure is such that the various changes in the supplying of oil and steam may be effected without materially altering the constructing hood.

Having thus described the invention what is claimed is:

1. An oil burner comprising a pan, a plate

- supported by said pan, said pan being formed with lugs, said plate being bolted to said lugs, a frusto-conical hood supported by said plate, said hood being formed with an 5 interiorly disposed support, a steam passage disposed longitudinally of said support, an oil passage disposed transversely of said support, said oil passage communicating with the said steam passage intermediate its 10 ends, a steam generator supported by said plate and disposed above said pan and a connection between said generator and said steam passage.
2. An oil burner comprising a pan, a plate 15 extending at right angles from said pan, a frusto-conical hood supported by said plate, said hood being formed with an interiorly disposed support, said support being formed with intersecting steam and oil passages, 20 and a plurality of plates slidably disposed upon said first mentioned plate.
3. An oil burner comprising a pan, a plate extending at right angles from said pan, a frusto-conical hood supported by said plate
- 25 said hood being formed with an interiorly disposed support, said support being formed with intersecting steam and oil passages, plates slidably disposed upon said first mentioned plate and pivoted locking means 30 co-acting with said plates to hold the same within the stove.
4. An oil burner comprising a pan, a plate 35 extending at right angles from said pan, a frusto-conical hood supported by said plate, said hood being formed with an interiorly disposed support, said support being formed with intersecting steam and oil passages, plates slidably disposed upon said first mentioned plate, and a plurality of locking members 40 for said slidable plates.

In testimony that I claim the foregoing as my own, I have hereto affixed my signature in the presence of two witnesses.

ITHAMER N. F. RANDOLPH.
